UNITED STATES PATENT OFFICE.

GEORGE M. GRAHAM, OF CHICAGO, ILLINOIS, ASSIGNOR TO G. A. EDWARD KOHLER, OF CHICAGO, ILLINOIS.

REINFORCED CONCRETE STRUCTURE.

No. 868,921.

Specification of Letters Patent.

Patented Oct. 22, 1907.

Application filed June 1, 1907. Serial No. 376,808.

To all whom it may concern:

Be it known that I, GEORGE M. GRAHAM, a citizen of the United States of America, and a resident of Chicago, in the county of Cook and State of Illinois, have 5 invented certain new and useful Improvements in Reinforced Concrete Structures, of which the following is a specification.

This invention relates to that type of concrete structures in which a series of wires forms the center of a 10 marginal frame to constitute a metal reinforce for the mass of concrete comprising a floor or other portion of a concrete structure. And the present improvement has for its object to provide a simple and efficient structural formation and combination of parts by means of 15 which the wire comprising such center, and consisting of a single continuous length of wire, is rove or laced back and forth upon the marginal supporting frame in a manner which admits of each individual strand, of the center so formed, being brought to a common and uniform 20 tension and in consequence assume in an equal and uniform degree the normal stress or load imposed during the process of erection, and in subsequent actual use, all as will hereinafter more fully appear.

In the accompanying drawings:—Figure 1, is a detail plan view showing the marginal frame and continuous wire center of a unit of the present reinforced concrete structure, before the concrete mass is applied. Fig. 2, is a detail vertical section of the completed structure. Fig. 3, is a detail sectional elevation of one 25 form of the runner brackets of the present construction, and around which the continuous wire which forms the center is rove and drawn. Fig. 4, is a detail plan view of the same. Fig. 5, is a detail plan view of another form of the runner bracket aforesaid. Fig. 6, is a detail 30 vertical section of the same. Figs. 7 and 8, are detail sectional elevations of still another form of the runner brackets aforesaid, and illustrating different positions in which the same are used. Fig. 9, is a face view of the 35 runner bracket last mentioned. Fig. 10, is a section 40 of the same, on line x—x, Fig. 9.

Similar numerals of reference indicate like parts in the several views.

Referring to the drawings, 1 represents a series of structural iron members of any usual form in cross section, and united together, at their meeting ends, or otherwise held in proper relation, to constitute a rectangular marginal frame, which in connection with the center of wire hereinafter described constitutes a skeleton reinforce unit for a floor or other portion of a reinforced concrete building or structure.

2 is the skeleton wire center of the marginal frame aforesaid, and such center in the present invention is formed by a series of wire strands arranged in spaced relation, and in crossed or opposite directions. Such

strands are connected to the marginal frame aforesaid 55 by the series of runner brackets hereinafter described, and by means of which a single continuous length of wire may be employed in forming the series of wire strands above referred to, and so that each individual strand can be brought to a common and uniform tension 60 to bear in an even and uniform manner the normal stress or load imposed upon the skeleton reinforce as a whole, the result being that a very strong and durable reinforce structure is provided with a minimum amount of metal. 65

The attainment of the results above described in an effective and practical manner, constitutes the main feature of novelty of the present invention, and comprises accordingly, a structural formation and arrangement of runner brackets for receiving the return bends 70 in the single wire comprising the skeleton reinforce center, and the connection of such brackets to the marginal frame, as follows:—

3, are the runner brackets above referred to, and which in the present construction are secured in a fixed 75 and substantial manner to the structural iron frame members 1 by means of integrally formed clips 4, or by fastening bolts 5, as hereinafter more fully set forth. The main or body portion of such brackets is either of a circular or semi-circular form, in accordance with 80 their particular employment in the present construction as hereinafter set forth, and in all cases will be formed with a grooved periphery to receive and hold the return bends in the single wire from which the reinforce center is formed. 85

As applied to the structural iron 1 beams, generally employed in building structures, to form a floor or other horizontal portion of the building, the said runner brackets will be attached to either the top or bottom, or both surfaces of said beams by means of curved clips 90 or hooks 4, integrally formed on the said main or body portion of the runner brackets, and having engagement with the flanges of the beams, as shown in Figs. 2, 3 and 6. While a single attaching clip 4 may be used as the means of attachment, it is preferable to use a pair 95 of the same, in spaced relation as shown in Figs. 1, 4 and 5, as affording a more stable attachment, adapted to resist the twisting stress upon the brackets as the single wire comprising the reinforce center is looped around the runner bracket and forcibly drawn into 100 proper position.

6, are integrally formed clips or tongues, formed on the runner brackets in opposed relation to the clips 4 aforesaid, and adapted to be bent around the other edge of the structural iron member 1, to prevent accidental disengagement for the runner bracket from said beam as illustrated in Figs. 2, 3, and 6.

As applied to the aforesaid beams 1, to form a wall or

other vertical part of a building, the runner brackets will be clamped to the edge of a horizontal flange of said beam, by the clamping bolts 5, extending transversely across the beam, and having hooked ends for engagement with the flange at the side of the beam opposite to where the runner brackets are attached. With such type of runner brackets the one side of the body portion of a bracket is formed with a recess or channel 7, adapted to fit an edge of the beam 1 to prevent a turning tendency of the runner bracket under the strain imposed in drawing the strands of the reinforce wire center into proper position. With a view to make such type of runner brackets reversible, duplicate channels 7 are formed therein and located equidistantly at opposite sides of the opening or orifice in the bracket body for the passage of the fastening bolt 5, as shown in Figs. 7, 8, 9 and 10.

The grooves the periphery of the runner bracket are preferably made of the substantially rectangular form shown in Figs. 3, 6 and 10, as it has been found in extensive practical experience that such form of groove offers the least resistance to the drawing of the wire into proper position.

A material part of the present invention consists in making the body of the runner bracket of a diameter equal to the distance between the individual strands of the reinforce wire center 2, with a view to impose a parallel relation on such strands, and at the same time provide a large abutment diameter around which the bends in the wire strands may be drawn with certainty and uniformity in the process of erection.

8, are ears arranged at the periphery of the runner brackets and adapted to be bent down over the peripheral grooves of the same, to hold the wires in place against accidental disengagement from such grooves.

In the practical application of the present invention, the structural iron members 1, will be secured in proper position in any usual manner, after which the runner brackets will be attached thereto in spaced relation. 40 A single continuous wire is then rove around the brackets in the manner illustrated in Fig. 1, to form the skeleton reinforce center of the structure, the wire being drawn around said brackets by suitable power means as the operation of applying the wire progresses.

45 It is preferable to connect the respective ends of the wire together by a clip or tie 9, as shown in Fig. 1, with the completion of the winding of the wire in crossed directions on the marginal frame 1, in the manner above set forth. It is however within the province of the present invention to use any other and suitable method of fixing the respective ends of each series of strands.

The semi-circular form of runner brackets heretofore described and as shown in Figs. 2 and 5, will be used on structural iron members 1, which are arranged at outer portions of a building structure; while the circular form of such runner brackets heretofore described, and as shown in Figs. 2, 3 and 4, will be used on structural iron members 1 which are arranged in the interior portions of the building structure and constitute a member in common of two adjacent marginal frames, with the circular runner brackets adapted to receive the return bends of two reinforce wire centers as illustrated to the right and to the bottom in Fig. 1.

While in the drawings the wire reinforce center is shown as individual to a single marginal frame, to form

a floor or other building unit, the scope of the present invention involves a marginal frame of any desired dimensions, so as to constitute an entire floor, side or other portion of the building, and provided with intermediate structural iron members over which the wire 70 reinforce center passes and is intermediately supported thereby.

Wire or other lathing may be used in connection with the reinforce center above described, so as to receive and hold the mass of concrete which constitutes 75 the floor or other portion of the building, as usual in the present class of reinforce concrete structures.

The present construction affords a ready means for attaining a hollow wall or floor construction, by the duplication of the reinforce center above described at opposite sides of the marginal frame 1, and as illustrated in Fig. 2.

The runner brackets described in detail in the foregoing description form the subject matter of divisional application for Letters Patent, Serial No. 389,653, filed 85 August 22, 1907, and accordingly no claim is made in this application to the structural formation of such bracket other than in combination with other coacting parts of a reinforced concrete structure as set forth in the claims.

Having thus fully described my said invention what I claim as new and desire to secure by Letters Patent, is:—

1. In a reinforced concrete structure, a marginal frame, a series of runner brackets fixedly attached thereto, and a 95 wire center formed of a single length of wire rove around said runner brackets, the runner portion of said brackets having a diameter approximating the spacing of the strands of wire comprising the wire center, substantially as set forth.

2. In a reinforced concrete structure, a marginal frame, a series of runner brackets fixedly attached thereto by integrally formed clips, and a wire center formed of a single length of wire rove around said runner brackets, the runner portion of said brackets having a diameter approximating 105 the spacing of the strands of wire comprising the wire center substantially as set forth.

3. In a reinforced concrete structure, a marginal frame, a series of runner brackets fixedly attached thereto, and a wire center formed of a single length of wire rove around 110 said runner brackets, the runner portion of said brackets having a semi-circular form and a diameter approximating the spacing of the strands of wire comprising the wire center, substantially as set forth.

4. In a reinforced concrete structure, a marginal frame, a series of runner brackets fixedly attached thereto by integrally formed clips and a wire center formed of a single length of wire rove around said runner brackets, the runner portion of said brackets having a semi-circular form 115 and a diameter approximating the spacing of the strands of wire comprising the wire center, substantially as set forth.

5. In a reinforced concrete structure, a marginal frame, a series of runner brackets fixedly attached thereto by oppositely arranged and integrally formed clips, and a wire 120 center formed of a single length of wire rove around said runner brackets, the runner portion of said brackets having a diameter approximating the spacing of the strands of wire comprising the wire center, substantially as set forth.

6. In a reinforced concrete structure, a marginal frame, a series of runner brackets fixedly attached thereto by oppositely arranged and integrally formed clips, and a wire center formed of a single length of wire rove around said runner brackets, the runner portion of said brackets having a semi-circular form and a diameter approximating 125 the spacing of the strands of wire comprising the wire center, substantially as set forth.

7. In reinforced concrete structure, a marginal frame, a series of runner brackets the body portions of which are formed with peripheral grooves rectangular in cross section and with oppositely arranged and integrally formed attaching clips, and a wire center formed of a single length of wire rove around said runner brackets, the runner portions of said brackets having a diameter approximating the spacing of the strands of wire comprising the wire center, substantially as set forth.
- 10 8. In reinforced concrete structure, a marginal frame, a series of runner brackets the body portions of which are formed with peripheral grooves rectangular in cross sec-

tion and with oppositely arranged and integrally formed attaching clips, and a wire center formed of a single length of wire rove around said runner brackets, the runner portions of said brackets having a semi-circular form and a diameter approximating the spacing of the strands of wire comprising the wire center, substantially as set forth. 15

Signed at Chicago, Illinois, this 23rd day of May, 1907.

GEORGE M. GRAHAM.
